UNITED STATES PATENT OFFICE.

EMMA FARRELL RUGGLES, OF NEW YORK, N. Y.

TOILET-SCISSORS.

1,205,029.

Specification of Letters Patent. Patented Nov. 14, 1916.

Application filed December 18, 1915. Serial No. 67,555.

To all whom it may concern:

Be it known that I, EMMA FARRELL RUGGLES, a citizen of the United States, and a resident of the city of New York, borough 5 of Brooklyn, in the county of Kings and State of New York, have invented a new and Improved Toilet-Scissors, of which the following is a full, clear, and exact description.

10 My invention relates to a toilet scissors and has for its prime object to give a blade of the scissors at the front end a form whereby a depressed nail, particularly a depressed toe nail, may be effectively raised 15 with facility and despatch and without any danger of cutting either the nail of the toe or finger.

The stated object of the invention is attained by forming the blade with a depressed upper side presenting a top surface 20 rounding transversely from the back edge of the blade toward the opposite side edge which latter constitutes the usual cutting edge of the blade and the said rounding surface 25 adjacent to the back or rear side of the blade presenting a gradual rise or upward incline, toward the rear end of the blade. At the said cutting edge there is the usual bevel at an angle to the lower flat 30 side of the blade so that the rounding lines are attained without interfering with the cutting function of the blade. Also, the lines of the rounding depressed portion merge into the front end of the blade, said 35 front of the blade being transversely rounded. Furthermore, the said rear edge of the blade at the depressed portion is in the form of a dull, non-cutting edge. The result of this novel formation of the front 40 end of the blade and the surfaces adjacent thereto, is that the blade may be readily entered beneath a depressed or ingrowing nail and by a transverse rocking movement of the blade, the nail may be quickly lifted 45 without injury to the toe or finger and the blade at the same time worked forwardly while beneath the nail so that the transversely rounding lines, coupled with the rear incline, enable the user to quickly restore 50 the nail to normal condition. Incidentally, the transversely rounded front end serves for forcing back the cuticle of the nail in a proper manner and the front cutting edge of the blade is available as usual for trimming 55 the said cuticle after it has been manipulated by the front end of the blade.

My improved scissors, in its preferred form, includes also, a nail file on the shank of one of the blades, the file being dovetailed into the shank to be firmly held in 60 position on the said shank flush with the upper surface thereof.

Reference is to be had to the accompanying drawings forming part of this specification in which similar reference characters 65 indicate corresponding parts in all the views.

Figure 1 is a plan view of a toilet scissors embodying my invention, the size being exaggerated beyond the actual size of scissors; 70 Fig. 2 is a back edge view thereof; Fig. 3 is a transverse section on the line 3—3, Fig. 2, on a scale much enlarged to better illustrate the distinctive formation at the front of the scissors; Fig. 4 is a fragmentary 75 longitudinal section on the line 4—4, Fig. 1, the view being on the same scale as Fig. 3; and Fig. 5 is a perspective view of the forward end of one of the blades enlarged to the scale of Figs. 3 and 4. 80

In constructing a practical embodiment of my invention in its preferred form scissors' blades 10 and 11 are given in general, the conventional form having finger-holds 12 at the rear ends of the shanks 13, the 85 blades being pivotally connected by a screw 14 in the usual manner.

The numerals 15, 16 (Fig. 3) designate the cutting edges of the respective blades, the numeral 17 indicating the usual bevel of the 90 blade 10 to produce, with the flat side of the blade, the cutting edge of the latter as usual.

At the forward end the blade 10 is depressed as at 18, the depression extending 95 from the front end 19 of the blade rearwardly. The surface of the depressed portion 18 presents lines rounding transversely from the back edge 20 of the blade toward the cutting edge 15. The transversely 100 rounding lines of the depressed portion 18 may be continued from the back edge 20 to a juncture with the bevel 17 of the cutting edge, but, in any event, the said surface will be rounded transversely adjacent to the 105 back edge 20 of the blade, the purpose of which will clearly appear as the description proceeds. At the rear end of the depression 18, there is a rise or incline 21, the transversely rounding surface lines being 110 continued at said incline. The juncture of the transversely rounding lines with the flat

lower side of the blade at the back is such as to produce a dull, non-cutting back edge at the depressed portion and such dull edge and the lines of the depressed portion merge 5 forwardly into the lines of the front end 19, said end 19 being transversely rounded.

With the described form of the blade, the same is manipulated as follows in raising a depressed nail: The blade is entered be- 10neath the nail either at the center or adjacent to the depressed corner of the nail, the blade being preferably entered endwise.

The rounded depressed portion at the back of the blade having been brought beneath 15 the nail, the blade is rocked transversely and at the same time advanced beneath the depressed side portion of the nail. The rocking of the blade and the gradual forward movement thereof eventually brings

20 the upwardly inclined rounding portion 21 beneath the depressed part of the nail so that the latter is quickly restored to its normal condition or, in any event, to a raised condition sufficient for the proper trimming

25 of the nail. In any case, a few applications of the blade to the nail will eventually restore it to its proper condition. The manipulation of the blade in thus restoring the nail involves no possible danger of cutting

30 the toe or finger by reason of the dull edges at the back and front. Incidentally, the described formation of the blade for treat- 35 ing a depressed or ingrowing nail, results in a proper form of the front end of the blade

for forcing back the cuticle about the nail. Also, since the rounding lines in no way interfere with the front cutting edge of the blade, or its bevel 17, said front edge at the depressed portion may be conveniently uti- 40 lized for trimming the cuticle after the same has been manipulated by the rounded end 19.

One of the shanks 13 of the scissors is, in

practice, equipped with a file 22, the said file ranging lengthwise with the shank to which it is attached and being let into the shank 45 and dove-tailed therein as best seen in Fig. 2, to lie flush with the side surface of the shank. Thus, the scissors provides an effective and convenient nail file in addition to the described formation for treating a de- 50 pressed or ingrowing nail.

Having thus described my invention I claim as new, and desire to secure by Letters Patent:

A pair of toilet scissors having one of its 55 blades formed with a broadened end portion, the end of which is curved radially outwardly and downwardly from a common point and terminates in a transversely curved under edge, the remaining portion of 60 said broadened end portion being trans- versely curved outwardly and downwardly and terminates in a substantially straight under side forming a cutting edge, the front portion of the remaining portion merging 65 with the curved end portion and receding rearwardly therefrom and having its rear portion inclined gradually upwardly and merging with the adjacent body portion of said blade to provide a wedge shaped side 70 edge at the rear of said under side edge, whereby to provide means at the end of said blade for manicuring the cuticle around a nail and means at the side of said blade to coöperate with the end means for elevat- 75 ing a nail when positioned therebeneath and moved longitudinally thereunder.

In testimony whereof I have signed my name to this specification in the presence of two subscribing witnesses.

EMMA FARRELL RUGGLES.
